US0D1096927S

(12) **United States Design Patent** (10) **Patent No.:** **US D1,096,927 S**
(45) **Date of Patent:** **** Oct. 7, 2025**

(54) **ELECTRONIC DEVICE**

(71) Applicant: **Elo Touch Solutions, Inc.**, Knoxville, TN (US)

(72) Inventor: **Jeffrey Haller**, Redwood City, CA (US)

(73) Assignee: **Elo Touch Solutions, Inc.**, Knoxville, TN (US)

(**) Term: **15 Years**

(21) Appl. No.: **29/916,531**

(22) Filed: **Nov. 13, 2023**

(51) LOC (15) Cl. **18-01**

(52) U.S. Cl.

USPC **D18/4.4; D18/12**

(58) **Field of Classification Search**

(57) **CLAIM**

The ornamental design for an electronic device as shown and described.

DESCRIPTION

FIG. 1 is a front isometric view of an electronic device showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the figures show portions of the electronic device that form no part of the claimed design.

1 Claim, 6 Drawing Sheets
